UNITED STATES PATENT OFFICE.

CHARLES ROSENBLUM, OF BROOKLYN, NEW YORK, ASSIGNOR TO KRISCHER'S MANUFACTURING CO., INC., OF BROOKLYN, NEW YORK, A CORPORATION OF NEW YORK.

TWO-PART BELT BUCKLE.

Application filed August 20, 1923. Serial No. 658,214.

To all whom it may concern:

Be it known that I, CHARLES ROSENBLUM, a citizen of the United States, residing at the city of New York, borough of Brooklyn, in the county of Kings and State of New York, have invented certain new and useful Improvements in Two-Part Belt Buckles, of which the following is a specification.

This invention relates to separable fasteners and has particular reference to that type of devices of the nature of belt or analogous buckles, each comprising two members hooked detachably to each other.

A two-part separable buckle, as ordinarily made, comprising interlocking loop and tongue members which are likely to separate accidentally or undesirably as a result of pressure, a blow, or other incident brought to bear upon one or the other buckle member or belt closely adjacent thereto. Among the objects, therefore, of my improvement is to construct a two-part buckle that may easily be assembled and disassembled as desired; that will not separate accidentally nor undesirably, and one that is neat in appearance, cheap in construction, and strong and dependable in use.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is an inside view of a preferred embodiment of the invention.

Fig. 2 is a longitudinal section on the line 2—2 of Fig. 1.

Fig. 3 is a detail of the snap or catch means, as seen from the arrow 3, Fig. 2.

Fig. 4 is a similar view showing the spring action while the connection or disconnection is being made.

Fig. 5 is a plan of the blank of the loop member.

Fig. 6 is a plan of the blank of the tongue portion.

Referring now more specifically to the drawings, I show a buckle consisting of a loop member 10 and a hook or tongue member 11, both made of any suitable sheet ma-

terial, such as metal, and stamped or otherwise shaped to have interlocking features. The member 10 is formed along one edge portion with a loop 12, between which and the main part is a slot 13 extending toward the stopping short of the ends of the loop. The loop 12 is off-set slightly at 14 from the plane of the main part to accommodate the companion member 11, and the plane of the loop is disposed at an acute angle of from 30 to 40° to said main part plane.

Along the extreme free edge of the loop, remote from the slot 13, are formed one or more pairs of spring lugs or catches 15, the catches extending in normally slightly spaced relation to each other and in a plane substantially perpendicular to the plane of the loop. Each catch has a lug or projection 15' extending away from the other catch. The neck part 16 of the catches is preferably somewhat longer than the thickness of the co-operating member so as to allow a certain degree of angular play or flexibility of the buckle when in use.

The tongue member 11 is formed along one edge portion with a tongue 17, of a width corresponding to the length of the slot 13 into or through which tongue passes as a hook in assembling the parts, and the length of the tongue is substantially the same as the width of the loop. The tongue is bent to lie in a plane at an acute angle to the plane of the main part of the tongue member, and hence the loop after assemblage lies against the tongue or between the tongue and the said main part of the tongue member.

Naturally the two main members will lie at an angle to each other while the tongue is passed through the slot and then they are swung around the off-set 14 as an axis into about the same plane into locked position, as in Figs. 1 and 2.

The tongue 17 is formed with as many holes or short slots 18 as there are pairs of catch lugs 15, and they are so disposed as to receive the pairs of catches directly therethrough when the parts are swung as just stated. The length of a slot 18 is substantially the same as the width of the neck of the double catch that is received by it, but the lugs 15' of the catches project laterally farther from each other than the length of the slot 18. Hence as the double catch passes through its slot 18 the two catches

are caused, by contact with the respective ends of the slot, to spring toward each other, a result provided for by the normal space 19 between the catches. Compare Figs. 3 5 and 4. Thus it will be understood that the auxiliary catch means will normally prevent accidental unhooking or premature separation of the parts, but a slight degree of force applied to the main parts of the 10 buckle in the usual direction will effect easily withdrawal of the catches from the slots 18, and the disconnection of the tongue and loop follows readily. It will be noted, furthermore that the locking or unlocking 15 of the catches and tongue slots is effected by the same motion or in the same direction as the usual hooking or unhooking, respectively, so that no time is lost and no special attention need be given the operation 20 to secure the desired result.

While this buckle is designed primarily and especially for use on belts for bathing suits, it will of course be understood that it may be employed also in many other capacities.

I claim:

1. A separable device comprising two main members having interlocking tongue and loop parts, the loop part comprising a

main body portion and a loop lying in a 30 plane at an acute angle to the plane of the body and carrying at its free edge a spring catch, and the tongue member comprising a main body portion lying substantially in the plane of the body portion of the loop member when assembled, and a tongue portion which after passing through the loop member lies substantially parallel to the loop portion and provided with an opening 35 through which said spring catch means in- 40 terlocks.

2. A two-part buckle having loop and tongue members connectible and discon- 45 nectible through angular movement between the parts and serving normally when connected to resist strain in the same plane, the tongue member being provided with a tongue having an opening therethrough and the loop member being provided with a loop co-operating with said tongue and be- 50 ing provided at its free edge with a pair of spring catches projectable through the tongue opening when the parts are assem- 55 bled to prevent accidental separation of the members.

In testimony whereof I affix my signature.

CHARLES ROSENBLUM.
